CLAIM

We claim the ornamental design for an electronic cable, as shown and described.

DESCRIPTION

FIG. 1 is an isometric top, right side view of a first embodiment of an electronic cable;

FIG. 2 is an isometric top, right side view of a second embodiment of an electronic cable;

FIG. 3 is an enlarged isometric top, right side view of a first embodiment of an electronic cable;

FIG. 4 is a top view thereof;

FIG. 5 is a bottom view thereof;

FIG. 6 is a left side view thereof;

FIG. 7 is a right side view thereof;

FIG. 8 is a rear view thereof;

FIG. 9 is a front view thereof;

FIG. 10 is an isometric top, right side view of a third embodiment of an electronic cable;

FIG. 11 is an isometric top, right side view of a fourth embodiment of an electronic cable;

FIG. 12 is an enlarged isometric top, right side view of a third embodiment of an electronic cable;

FIG. 13 is a top view thereof;

FIG. 14 is a bottom view thereof;

FIG. 15 is a left side view thereof;

FIG. 16 is a right side view thereof;

FIG. 17 is a rear view thereof;

FIG. 18 is a front view thereof;

FIG. 19 is an isometric top, right side view of a fifth embodiment of an electronic cable;

(Continued)

FIG. 20 is an isometric top, right side view of a sixth embodiment of an electronic cable;
 FIG. 21 is an isometric top, right side view of seventh embodiment of an electronic cable;
 FIG. 22 is an enlarged isometric top, right side view of a fifth embodiment of an electronic cable;
 FIG. 23 is a top view thereof;
 FIG. 24 is a bottom view thereof;
 FIG. 25 is a left side view thereof;
 FIG. 26 is a right side view thereof;
 FIG. 27 is a rear view thereof;
 FIG. 28 is a front view thereof;
 FIG. 29 is an isometric top, right side view of an eighth embodiment of an electronic cable;
 FIG. 30 is an isometric top, right side view of a ninth embodiment of an electronic cable;
 FIG. 31 is an isometric top, right side view of a tenth embodiment of an electronic cable;
 FIG. 32 is an enlarged isometric top, right side view of an eighth embodiment of an electronic cable;
 FIG. 33 is a top view thereof;
 FIG. 34 is a bottom view thereof;
 FIG. 35 is a right side view thereof;
 FIG. 36 is a left side view thereof;
 FIG. 37 is a rear view thereof; and,
 FIG. 38 is a front view thereof.

The evenly spaced broken lines in the drawings depict portions of the embodiments of the electronic cable which form no part of the claim.
